US0D1094414S

(12) **United States Design Patent** (10) **Patent No.:** **US D1,094,414 S**
Peittersen et al. (45) **Date of Patent:** **** Sep. 23, 2025**

(54) **DISPLAY SCREEN OR PORTION THEREOF WITH A GRAPHICAL USER INTERFACE WITH A CIVILITY SCORE**

(71) Applicant: **Seekr Technologies Inc.**, Vienna, VA (US)

(72) Inventors: **Rachel Peittersen**, Vienna, VA (US); **Gregory Bauwens**, Vienna, VA (US)

(73) Assignee: **SEEKR TECHNOLOGIES INC.**, Vienna, VA (US)

(**) Term: **15 Years**

(21) Appl. No.: **29/938,749**

(22) Filed: **Apr. 23, 2024**

(51) LOC (15) Cl. **14-04**

(52) U.S. Cl.

USPC **D14/485**

CLAIM

The ornamental design for a display screen or portion thereof with a graphical user interface with a civility score as shown and described.

DESCRIPTION

FIG. 1 is a first embodiment of a display screen or portion thereof with a graphical user interface with a civility score; and,

FIG. 2 is a second embodiment thereof.

The outermost broken lines show the display screen or portion thereof and form no part of the claimed design. The broken lines within the figures show portions of the graphical user interface that form no part of the claimed design.

1 Claim, 2 Drawing Sheets
